United States Patent Office.

GEORGE W. NELL, OF PHILADELPHIA, PENNSYLVANIA.

Letters Patent No. 89,883, dated May 11, 1869.

IMPROVED CURTAIN-FIXTURE.

The Schedule referred to in these Letters Patent and making part of the same.

To all whom it may concern:

Be it known that I, GEORGE W. NELL, of Philadelphia, in the county of Philadelphia, and State of Pennsylvania, have invented a new and improved Window-Shade Fixture; and I do hereby declare that the following is a full, clear, and exact description thereof, which will enable those skilled in the art to make and use the same, reference being had to the accompanying drawings, forming part of this specification, in which—

Figure 1 is a side view of my improved shade-fixture;

Figure 2 is a horizontal section of the same, taken on the line *x x*, fig. 1;

Figure 3 is a side view of the old fixture heretofore used; and

Figure 4 is a horizontal section of the same, taken on the line *y y*, fig. 3.

Similar letters of reference indicate corresponding parts.

This invention relates to an improved cord-tightener for window-shade fixtures; and

It consists in the combination of the hook with the toothed plate, when the latter is grooved longitudinally to receive a pin or rib formed upon the hook for the purpose of preventing the same from being moved laterally upon the plate, and thereby displaced.

The following are some of the advantages of my improved fixture:

It can be easier set than the ordinary fixtures, occupies less room, and is shorter, and has, nevertheless, a longer space for adjustment than the same; the hook cannot be lost after having been applied, even if the cord should break, and it is much cheaper than any of the other fixtures, as both pieces of which it consists can be cast.

A, in the drawing, represents a plate or bar, made of cast-iron, or other suitable material.

It has, at its ends, two depressed ears or fastening-plates, *a*, by means of which it can be secured to the

window-frame, so that the body of the plate projects from the frame, as shown.

The inner face of the plate A is toothed near the edge, or entirely, as indicated in figs. 1 and 2.

B is an S-shaped hook, having one end forked to slide on and fit over the plate A, as shown.

The cord C is fitted over the outer part, *b*, of the hook, in the manner indicated in fig. 1, while the inner ends, *c*, of the hook fit against the teeth, *d*, of the plate.

The hook is thus, by the teeth, held in any desired position, the cord drawing its ends, *c*, firmly against them; but if desired, the hook can be easily adjusted.

A groove may be formed in the outer face of the plate A, and a pin, *e*, from the hook, may fit into the same, as in fig. 2, to prevent lateral play of the hook.

I am aware that the device illustrated in figs. 3 and 4 has already been in use.

In this device, a slotted plate, A', is used, together with a hook, B', said hook having a head, *f*, at its inner end, which it fitted through the slot, as shown, to engage in the teeth of the plate.

In this device, the plate A' is not only too weak, but also the shank of the hook lacks sufficient strength, and the hook is liable to be lost, and to lateral play, all of which inconveniences are overcome by my invention.

A friction-roller may be arranged on the arm *b* of the hook B, when the cord is fitted over the same.

I claim as new, and desire to secure by Letters Patent—

The combination of the S-shaped hook B with the toothed plate A, when the latter is provided with a longitudinal groove to receive the rib or pin *e*, formed upon the hook for the purpose of preventing the lateral play of the same, as herein shown and described.

GEO. W. NELL.
